UNITED STATES PATENT OFFICE

127,599

DESIGN FOR A PAIR OF SPECTACLES

Norman William Chappell, Amersham, England

Application August 2, 1940, Serial No. 94,150

Term of patent 14 years

To all whom it may concern:

Be it known that I, Norman William Chappell, a subject of the King of Great Britain, residing at Hithermead, Westanley Avenue, Amersham, Buckinghamshire, England, have invented a new, original, and ornamental Design for a Pair of Spectacles, of which the following is a specification, reference being had to the accompanying drawing, forming part thereof.

Figure 1 is a side elevational view of a pair of spectacles showing my new design,

Figure 2 is a perspective view looking towards the front of the spectacles,

Figure 3 is a top plan view, parts of the temple being broken away for convenience of illustration, and

Figure 4 is a sectional view on line 4—4 of Figure 2.

The dominating features of my design are shown in full lines on the drawing.

I claim:

The ornamental design for a pair of spectacles, as shown and described.

NORMAN WILLIAM CHAPPELL.
